FIG. 2.

THE BIRDS OF THE BAHAMAS

A technical line drawing of a brush assembly. It features a central vertical tube labeled 51. Two curved, ribbed brushes, labeled 77, are positioned on either side of the tube. Each brush is supported by a bracket labeled 76. A label 43 is positioned above the top bracket. The assembly is shown in a perspective view, with the tube extending downwards and the brushes curving outwards.

GEAR TOOTH FACE FINISHING APPARATUS AND METHOD

David A. Wallace, Detroit, Mich., assignor to
Chrysler Corporation, Highland Park, Mich., a
corporation of Delaware

Application June 20, 1942, Serial No. 447,796

14 Claims. (Cl. 51—64)

This invention relates to an improved gear tooth surface finishing apparatus and method.

More particularly, the invention pertains to improvements in an apparatus and method for finishing the face surfaces of gear teeth of diverse contours by an abrading action during which are produced between such surfaces and an abrading member, simultaneous relative movements in a plurality of different directions including the one in which the face surfaces of meshed gear teeth move relative to each other during operation.

One of the main objects of the invention is to provide gear teeth face surface finishing apparatus by which is removed substantially only the metal that has been disturbed by previous grinding and machining operations without significantly varying a previously established tooth face contour.

Another object of the invention is the provision in apparatus of this kind for simultaneously applying abrading members to opposite side face portions of a gear tooth with substantially equal pressure of a controllable low order.

A further object of the invention is the provision of mechanism in finishing apparatus of this kind for simultaneously producing between a gear tooth and an abrading element relative reciprocative movements both depthwise and lengthwise of the tooth and relative oscillative movement thereof about the normal axis of the gear on which it is provided while the abrading element is in contact with the face of the tooth.

An additional object of the invention is to provide apparatus of this kind which produces the foregoing oscillative and reciprocative movements at speeds of predetermined and different values.

Illustrative embodiments of the invention are shown in the accompanying drawings in which:

Fig. 1 is a perspective view of gear tooth finishing apparatus embodying the invention and illustrating the performance of the improved method.

Fig. 2 is an enlarged, fragmentary perspective view of the tool and work holding units of the apparatus shown in Fig. 1.

Fig. 3 is a fragmentary sectional view taken on the line 3—3 of Fig. 2.

Fig. 4 is a fragmentary sectional view taken on the line 4—4 of Fig. 1.

Fig. 5 is an enlarged, fragmentary plan view showing the abrading elements and gear tooth face surfaces, illustrated in Fig. 1, in operative engagement.

Fig. 6 is a fragmentary plan view, partly in section, of a yieldable abrading element holder embodying a modified form of the invention.

Fig. 7 is a fragmentary sectional view taken on the line 7—7 of Fig. 1.

In the form of the invention illustrated in the drawings, the improved gear tooth face finishing apparatus comprises a frame-like base structure generally designated by the numeral 10 on which are mounted spaced bearing blocks 11 having registering vertically aligned bores therein. A vertically reciprocable shaft 12 is oscillatively journalled in the bores of the blocks 11 and pivotally connected at its lower end to a crank arm 13 by a universal joint element 14. The universal joint element 14 has a flange 15 pivotally connected by a pin 16 to a bifurcated end portion 17 on the lower extremity of the shaft 12. The universal joint element 14 comprises a plate 18 having a downwardly extending stud 19 journalled in an aperture 20 formed in a web portion 21 provided at the upper end of the crank arm 13. The lower end of the crank arm 13 is journalled on an eccentric 22 which is driven through a gear unit 23 by a motor 24. The motor 24 is drivingly connected by pulleys 25 and 26 and a belt 27 to the driving shaft of the gear unit 23. The rotation of the eccentric 22 produces vertical reciprocatory movement of the shaft 12.

The shaft 12 is drivingly oscillated by a motor 28 connected through pulleys 29 and 30 and a belt 31 with a gear unit 32. The final driven shaft 33 of the gear unit 32 is disposed vertically, as illustrated in Fig. 1, and provided at its upper end with a crank member having a crank pin 34. Pivotally mounted on the crank pin 34 is a lever 35 which is supported at the left side of the apparatus, as viewed in Fig. 1, by a bracket 36 having a slot 37 therein in which the left end of the lever 35 is slidably mounted. The shaft 12 is operatively connected with the lever 35, intermediate the ends of the latter, by a yoke 38 having a pin 39 extending between its vertically aligned arms and projecting through an aperture formed in the lever 35. As the crank pin 34 is revolved about the axis of the final driven shaft 33 it reciprocates the lever 35 thereby oscillating the shaft 12 while it is simultaneously reciprocated by the eccentric 22, the space between the arms of the yoke 38 being sufficient to accommodate this reciprocatory movement as the pin 39 slides vertically relative to the lever 35.

Mounted on the upper end of the shaft 12 is a work supporting plate 40 having a spindle 41 extending upwardly therefrom in co-axial align-

ment with the oscillative axis of the shaft 12. The spindle 41 is adapted to receive a gear 42 having a tooth 43 provided with face portions to be finished. The gear 42 may be releasably held in a fixed position with respect to the shaft 12 and work supporting plate 48 by a suitable clamping collar 44 mounted on the upper end portion of the spindle 41 and a hand bolt 45 threaded on the threaded extremity 46 of the spindle. Suitable indexing mechanism (not shown) may also be employed for releasably holding the gear against rotation relative to the shaft 12 and accommodating movement of successive teeth of the gear into position to receive a finishing operation. A gear mounted as illustrated in Fig. 2 of the drawings is suitably fixed against movement relative to the spindle 41. It is thus simultaneously reciprocated vertically, lengthwise of the gear teeth, and oscillated about the normal axis of the gear.

Mounted on the top of the frame structure 10 is a plate 47 having spaced guide rails 48 thereon between which is shiftably mounted a tool support member 49. The guide rails 48 are so positioned as to confine reciprocative movement of the tool support member 49 to a path extending depthwise of the tooth 43 which is positioned for receiving a finishing operation. Mounted on the shiftable tool support 49 is a finishing tool generally designated by the numeral 50 which comprises a block 51 having a pair of abrading element holders 52 pivotally mounted thereon at 53 and 54 respectively. Each holder 52 has an abrading element 56 extending outwardly therefrom and adapted to engage opposite face portions of the tooth 43 in embracing relationship as illustrated in Fig. 5. The outer end portions of the abrading elements 56 are shaped to conform generally to the contour of the opposite face portions of the tooth 43. Each abrading element holder 52 has a box-like structure 57 on its forward end provided with a removable clamping plate 58 by which the abrading elements 56 are removably held in place. A bolt 59 extends through registering apertures in the abrading element holders 52 and is provided on one end with a spring 60 which may be adjustably compressed by a nut 61 threaded on the bolt for the purpose of resiliently yieldably urging the abrading element holders 52 toward each other about their pivots 53 and 54 in order to yieldably apply the outer end portions of the abrading elements 56 to the opposite face portions of the tooth 43 with abrading pressure.

The tool support member 49 and the abrading tool structure mounted thereon is drivingly reciprocated in a direction generally depthwise of the gear tooth being finished by a motor 62 mounted on the plate 47 of the frame 10. The motor 62 has a vertically disposed shaft 63 provided on its lower extremity, as illustrated in Fig. 4, with an eccentrically located driving pin 64. The driving pin 64 extends into a transverse slot 65 formed in a shiftable cross head member 66 which is rigidly connected by a bar 67 and block 68 with the reciprocable tool support member 49, as illustrated in Fig. 1. Rotation of the motor shaft 63 reciprocates the cross head 66 which in turn reciprocates the tool support 49 and the abrading tool structure carried thereby. This action produces reciprocation of the abrading elements 56 in the direction of the depth of the tooth operated upon.

In the preferred operation of the foregoing

finishing apparatus the gear is reciprocated axially of its normal axis at a rate of from 100 to 150 reciprocations per minute and throughout a stroke depending upon the length of the gear teeth being finished and the comparative width of the abrading elements 56. In finishing a gear of the dimensions illustrated in the drawings with the aid of abrading elements of the dimensions shown, the stroke of this reciprocative movement may be from one-fourth of an inch to three-eighths of an inch in length. The gear is simultaneously oscillated about its normal axis at a rate of from 150 to 200 oscillations per minute throughout an arc of sufficient amplitude to bring the abrading elements into contact with substantially the full depth of the tooth face portions. The abrading elements 56 are reciprocated generally depthwise of the tooth operated upon at a rate of from 700 to 900 reciprocations per minute and throughout a stroke of approximately one-sixteenth of an inch. All of these reciprocative and oscillative movements are preferably simultaneously produced in order to distribute the abrading action uniformly over the entire face portions of the tooth and to avoid re-tracing the same path by localized hard points in the abrading elements. The abrading elements are preferably applied to the face portions of the tooth with relatively low pressure in the presence of a suitable lubricant. When finishing with relatively low pressures by a multiplicity of movements of the above order and in the presence of suitable lubricants, the finishing operation removes only that portion of the metal which has been disturbed by a prior machining or grinding operation and does not significantly vary a previously established tooth face contour.

If desired, the oscillating movement of the gear and its reciprocative movement may be employed while the abrading elements are held at rest or the gear may be oscillated about its normal axis without reciprocating it while the abrading elements are reciprocated depthwise of the tooth operated upon. It is however, found that the best results are obtained by conducting the three foregoing relative movements between the work and the abrading elements simultaneously.

In the form of the invention illustrated in Fig. 6, a pair of series of leaf spring elements 75 are rigidly mounted at their rear ends on the block 51. The long leaves 75 of each series of leaf springs is provided with an abrading element holder 76 in which is mounted an abrading element 77. The abrading elements and the gear tooth operated upon with this form of the apparatus undergo the relative oscillative and reciprocative movements set forth above.

Although but several specific embodiments of the invention are herein shown and described, it will be understood that various changes in the sequence of operations, steps and materials employed may be made without departing from the spirit of the invention.

I claim:

1. Gear tooth face finishing apparatus comprising relatively oscillatable and reciprocable work and tool support members, means on said work support member for positioning a tooth of a gear having a face portion to be finished for receiving a finishing operation, means for confining the relative reciprocative movement of said members to a course extending depthwise of said tooth and transversely of the axis of the

relative oscillative movement thereof, means for confining the relative oscillative movement between said members about a fixed axis an abrading tool on said tool support member having an abrading element extending into contacting proximity with respect to said face portion including means for yieldably urging said element into abrading contact with said face portion, and mechanism for drivingly simultaneously repeatedly producing said reciprocative and oscillative movements at respectively different rates while said element is in abrading contact with the face portions of the same tooth.

2. Gear tooth face finishing apparatus comprising relatively oscillatable and reciprocable work and tool support members, means on said work support member for positioning a tooth of a gear having a face portion to be finished for receiving a finishing operation, means for confining the relative reciprocative movement of said members to a course extending parallel to the axis of the relative oscillative movement thereof, an abrading tool on said tool support member having an abrading element extending into contacting proximity with respect to said face portion including means for yieldably urging said element into abrading contact with said face portion, and mechanism for drivingly simultaneously producing said reciprocative and oscillative movements at respectively different rates while said element is in abrading contact with face portion of said tooth.

3. Gear tooth face finishing apparatus comprising tool and work support members, mechanism mounting said members for relative oscillatable movements and stages of relative reciprocative movements in transverse directions, means on said work support members for positioning a tooth of a gear having a face portion to be finished for receiving a finishing operation, said mounting mechanism including means for confining one of said stages of reciprocative movement to a course extending normal to said axis and depthwise of said tooth and the other stage of reciprocative movement to a course extending lengthwise of said tooth, an abrading tool on said tool support member having an abrading element extending into contacting proximity with respect to said face portion and including means for yieldably urging said element into abrading contact with said face portion, and mechanism for drivingly simultaneously producing said oscillative and said two stages of reciprocative movement at respectively different rates while said element is in an abrading contact with said face portion of said tooth.

4. A gear tooth face finishing apparatus including an oscillatable work support member, means on said member for mounting a gear for oscillation therewith about a fixed axis coincident with its normal axis and for positioning a tooth of said gear having a face portion to be finished for receiving a finishing operation, a tool support member, an abrading tool shiftably mounted on said tool support member for reciprocation transversely of said axis depthwise of said tooth including an abrading element extending into overlapping relationship with respect to said tooth and having means for urging said element into abrading engagement with said face portion, and mechanism for drivingly simultaneously producing said oscillative movements and a plurality of said reciprocative movements during each half cycle of said oscillative movements.

5. Gear tooth face finishing apparatus includ-

ing an oscillatable work support member, means shiftably mounting said member for reciprocative movement substantially parallel to its oscillative axis, means on said member for mounting a gear for oscillation therewith about its normal axis and reciprocation therewith substantially parallel to said axis and for positioning a tooth of said gear having a face to be finished to receive a finishing operation, a tool support member, an abrading tool shiftably mounted on said tool support member for reciprocation transversely of said axis depthwise of said tooth including an abrading element extending into overlapping relationship with respect to said tooth and having means for urging said element into abrading engagement with said face portion, and mechanism for drivingly simultaneously producing said oscillative movements said reciprocative movements in said direction parallel to said axis and a plurality of said transverse reciprocative movements during each half cycle of said oscillative movements.

6. Gear tooth face finishing apparatus comprising relatively oscillatable abrading tool and work support members, means on said work support member for positioning a tooth of a gear having a face portion to be finished for receiving a finishing operation, an abrading tool holder shiftably mounted on said tool support for reciprocative movement depthwise of said tooth, an abrading element movably mounted on said tool holder and extending into contacting proximity with respect to said tooth face portion, means for yieldably urging said element into abrading contact with said face portion, and mechanism for drivingly simultaneously producing said reciprocative and oscillative movements, said mechanism being so constructed and arranged as to produce a plurality of said reciprocative movements during each half cycle of said oscillative movements.

7. Gear tooth face finishing apparatus comprising relatively oscillatable and reciprocable work and tool support members, means on said work support member for positioning a tooth of a gear having a face portion to be finished for receiving a finishing operation, means for confining the relative reciprocative movement of said members to a course extending depthwise of said tooth and transversely of the axis of the relative oscillative movement thereof, an abrading tool on said tool support member having an abrading element engageable with the face portion of opposite sides of said tooth respectively and including means for resiliently urging said elements into abrading engagement with said face portion, and mechanism for drivingly simultaneously producing said oscillative movements and a plurality of said reciprocative movements during each half cycle of said oscillative movements.

8. Gear tooth face finishing apparatus comprising relatively oscillatable and reciprocable work and tool support members, means on said work support member for positioning a tooth of a gear having opposite face portions to be finished for receiving a finishing operation, means for confining the relative reciprocative movement of said members to a course extending parallel to the axis of the relative oscillative movement thereof, an abrading tool on said tool support member having abrading elements deflectively mounted thereon and engageable with the face portions of opposite sides of said tooth respectively and including means for resiliently urging said elements into abrading engagement with said

face portions during oscillation of said work, and mechanism for drivingly simultaneously producing said reciprocative and oscillative movements at respectively independent rates.

9. Gear tooth face finishing apparatus comprising tool and work support members, mechanism mounting said members for relative oscillatable movements and stages of relative reciprocative movements in transverse directions, means on said work support member for positioning a tooth of a gear having opposite face portions to be finished for receiving a finishing operation, said mounting mechanism including means for confining one of said stages of reciprocative movement to a course extending depthwise of said tooth and the other stage of reciprocative movement to a course extending lengthwise of said tooth, an abrading tool on said tool support member having abrading elements engageable with the face portions of opposite sides of said tooth respectively and including means for resiliently urging said elements into abrading engagement with said face portions, and mechanism for drivingly simultaneously producing said oscillative and said two stages of reciprocative movement including independent driving means for individually predetermining the rate of each of said movements.

10. Gear tooth face finishing apparatus including an oscillatable work support member, means shiftably mounting said member for reciprocative movement substantially parallel to its oscillative axis, means on said member for mounting a gear for oscillation therewith about its normal axis and reciprocation therewith substantially parallel to said axis and for positioning a tooth of said gear having a face to be finished to receive a finishing operation, a tool support member, an abrading tool shiftably mounted on said tool support member for reciprocation transversely of said axis depthwise of said tooth including a pair of abrading elements, each extending into overlapping engagement with the face portions of one of the opposite sides of said tooth respectively and having means for urging said elements with substantially equal pressure into abrading engagement with said opposite face portions, and mechanism for drivingly simultaneously producing said reciprocative and oscillative movements including means for producing a plurality of said reciprocations depthwise of said tooth during each half cycle of said oscillative movements of said gear.

11. Gear tooth face finishing apparatus comprising tool and work support members, mech-

anism mounting said members for relative oscillatable movements and stages of relative reciprocative movements in transverse directions, means on said work support member for positioning a tooth of a gear having face portions to be finished for receiving a finishing operation, said mounting mechanism including means for confining one of said stages of reciprocative movement to a course extending depthwise of said tooth and the other stage of reciprocative movement to a course extending lengthwise of said tooth, an abrading tool on said tool support including a pair of spring arms each provided with an abrading element for engaging one of the opposite face portions of said tooth respectively, said arms being biased toward each other for yieldably applying said abrading elements to said face portions, and mechanism for drivingly simultaneously producing said oscillative and said two stages of reciprocative movement.

12. The method of finishing face portions of a gear tooth comprising the steps of producing between an abrading element and a face of a gear tooth simultaneous relative oscillative movements and a plurality of reciprocative movements depthwise of said tooth during each half cycle of said oscillative movements and yieldably urging said face portions and abrading element together.

13. The method of finishing face portions of a gear tooth which comprises the steps of yieldably urging an abrading element into abrading contact with a face portion of said gear tooth, and producing between said abrading element and face portion simultaneous relative oscillative movements about the axis of said gear and reciprocative movements both depthwise and lengthwise respectively of said tooth and at respectively different rates.

14. The method of finishing face portions of opposite sides of a gear tooth which comprises the steps of yieldably urging each of a pair of abrading elements having abrading surfaces conforming generally with the contour of said face portions into abrading engagement with the latter, and producing between said abrading elements and said face portions simultaneous relative oscillative movements and reciprocative movements, both lengthwise and depthwise of said gear tooth, said depthwise reciprocative movements occurring throughout a plurality of cycles during each half cycle of said oscillative movements.

DAVID A. WALLACE.
